United States Patent Office

Des. 204,644
Patented May 3, 1966

204,644

ADDING MACHINE

Chester J. Abend, Camillus, and Robert S. Metzner, Syracuse, N.Y., assignors to SCM Corporation, a corporation of New York

Filed Feb. 24, 1964, Ser. No. 78,753

Term of patent 14 years

(Cl. D64—11)

FIGURE 1 is a front perspective view of an adding machine showing our new design;

FIGURE 2 is a front elevational view thereof;

FIGURE 3 is a left side elevational view;

FIGURE 4 is a top plan view; and

FIGURE 5 is a rear elevational view thereof.

The dominant features of our design are shown in full lines.

We claim:

The ornamental design for an adding machine, substantially as shown and described.
